GOTTLOB LUX, OF BERLIN-CHARLOTTENBURG, GERMANY, ASSIGNOR TO WESTINGHOUSE ELECTRIC & MANUFACTURING COMPANY, A CORPORATION OF PENNSYLVANIA

TANK LINING

Application filed June 7, 1926, Serial No. 114,048, and in Germany July 20, 1925.

My invention relates to fluid-immersed electrical apparatus and particularly to insulating linings for the containers thereof.

One object of my invention is to provide sectional linings for the containers of fluid-immersed electrical apparatus.

Another object of my invention is to provide linings for the tanks of fluid-immersed electrical apparatus that shall permit circulation of the fluid against the tank walls.

10 Another object of my invention is to provide linings for the containers of fluid-immersed electrical apparatus that shall insulate the electrical apparatus from the walls of the containers and also permit a circulation of the immersing fluid against the relatively cool walls of the containers.

In electrical apparatus such as transformers, circuit interrupters and the like, it is customary practice to provide linings for the metal tanks that serve to insulate the electrical apparatus from such metal tanks. The insulating materials commonly used for the linings are relatively poor conductors of heat. Since the capacity of electrical apparatus of many types is determined by their ability to radiate heat through the insulating fluid and the tank lining, it is necessary to provide the apparatus with a large radiating surface.

20 I propose to secure more efficient heat radiation by providing a sectional tank lining that shall permit the insulating fluid to circulate therethrough and come into contact with the cooler tank wall, and, at the same time shall overlap the sections in order that an electrical insulating barrier shall be interposed between the tank wall and the electrical apparatus.

25 In the accompanying drawings, Fig. 1 is a view, partially in elevation and partially in section, of a circuit interrupter embodying my invention.

Fig. 2 is a similar view of a modified form 30 of my invention.

Referring to Fig. 1, my invention comprises, in general, an electrical circuit interrupter 1 having the usual stationary contact members 2 and bridging member 3 that are suspended in a body of insulating fluid 4,

such as oil, contained in a tank 5 that is protected from the current-carrying electrical parts of the device by an insulating lining 6.

While I have shown my invention as applied to a circuit interrupter 1, it is to be understood that the invention is equally applicable to fluid-immersed transformers, reactors and the like.

35 The stationary contact members 2 and the bridging member 3 may be of any preferred construction, as they constitute no part of the present invention, except in so far as they are necessary to complete the several combinations hereinafter described and claimed.

40 The tank lining 6 comprises a plurality of 45 annual bands 7 of micarta or other suitable insulating material. Each of the bands 7 has the shape of a segment of a cone in order that its upper edge may be secured, by insulating rivets 8, to insulating supports 9 mounted in the tank 5.

45 By reason of the taper of the several bands 7, a plurality of openings 11 are formed between adjacent bands, through which the insulating fluid 4 may circulate. The bands 7 are secured to supports 9 in overlapping relation in order that an electrical insulating barrier shall exist between the current-carrying contact members 2 and the bridging members 3 and the metallic wall of the tank 5.

50 When current is traversing the circuit interrupter 1 and, particularly, when an arc is drawn therein, heat is generated which must be radiated therefrom. Accordingly, convection currents are set up in the insulating fluid 4 which tend to move upwardly, outwardly, and downwardly along the tank walls where they engage the tank lining 6. Such currents flow through the openings 11 and come directly into engagement with the metallic wall of the tank 5. By reason of the direct engagement of the fluid 4 with the tank 5 it is possible to radiate the heat generated within the circuit interrupter 1 without the time lag experienced, and the large radiating 55 surface required, where the tank lining is continuous and is interposed between the insulating fluid 4 and the tank wall.

55 In Fig. 2, I show a modified form of my invention in which the tank lining 6 is com- 60

pose of a plurality of bands 12 that are also annular in form but of uniform diameter. The bands 12 are disposed in overlapping relation upon the supports 9 in an alternate internal and external arrangement so that openings 13 are provided between the adjacent bands 12. The operation of this form of my invention is similar to that described in connection with the modification shown in Fig. 1.

10 It will thus be seen that I have provided a lining for the containers of immersed electrical apparatus that permits a circulation of the cooling medium directly in contact with the metallic wall of the container and, at the same time, provides an electrical insulating barrier between such apparatus and the container wall.

15 It is to be understood that such changes in the shape, form and arrangement of the component parts of my invention may be made as shall be within the scope of the appended claims.

20 I claim as my invention:

25 1. In an electrical apparatus, the combination with a tank, an electrical device mounted in the tank, and insulating fluid surrounding the electrical device, of a lining for the tank having a plurality of overlapping conical sections of insulating material spaced apart 30 to provide openings to permit circulation of the insulating fluid therebetween without materially reducing the insulating qualities thereof.

35 2. In an electrical apparatus, the combination with a tank, an electrical device mounted in the tank, and insulating fluid surrounding the electrical device, of an insulating lining for the tank having a plurality of overlapping tapered sections spaced apart to provide 40 openings throughout its entire length to permit circulation of the insulating fluid into engagement with the tank wall and providing an insulating barrier between the electrical device and the tank wall.

45 3. In an electrical apparatus, the combination with a tank, an electrical device mounted in the tank, and insulating fluid surrounding the electrical device, of a lining for the tank having a plurality of overlapping insulating sections of conical shape spaced apart to provide 50 a plurality of openings throughout its entire length to permit circulation of the insulating fluid into engagement with the tank wall without materially shortening the arc path thereto.

55 In testimony whereof, I have hereunto subscribed my name this 7th day of May, 1926.

GOTTLÖB LUX.
